LIQUID BRAKES

René Gassot, 8 bis, Villa Collet, Paris, France
 Filed Feb. 11, 1958, Ser. No. 714,649
 Claims priority, application France Feb. 19, 1957
 3 Claims. (Cl. 188—90)

The object of this invention is to provide certain improvements in the type of fluid brake described in the applicant's earlier U.S. Patent No. 2,750,008 wherein there is shown (see FIG. 3, reference numeral 17) a piston which compensates for the difference in volume which occurs in the control duct whenever one of the driven pistons of a vane is pushed back into the control duct.

This compensating piston is difficult to construct, and must in any case be capable of extremely rapid movements. The vanes illustrated are pushed back into their housings by the liquid pressure in the braking duct, this pressure being exerted on only one side of the vanes and being so high that it may damage the vanes and their housings. The improvements of the present invention overcome these two objections.

In order that the nature of the improvements may be readily ascertained, an embodiment of liquid brake in accordance therewith is hereinafter particularly described with reference to the accompanying drawings, wherein:

FIG. 1 is a vertical section through the fluid brake.

FIG. 2 is a side elevation of a vane, to a larger scale.

FIG. 3 is a part section, taken in a radial plane of the brake, to show mechanical locking means.

FIG. 4 is a part section, taken in a radial plane of the brake, to show braking pressure control means.

FIG. 5 is a cross-section of a portion of the vane, to an enlarged scale.

The brake shown in FIG. 1 has a cylindrical stator 1 and a rotor 2 coaxial therewith, an annular channel 3 defined between them being filled with liquid.

In the stator are provided three arcuate passages symmetrically disposed and serving as housings for three arcuate vanes 4, 4¹, 4¹¹ which have a sliding fit in their respective passages. The arcuate passages open into the channel 3, and their vanes are movable to bring one end out into the channel 3. The vanes are symmetrically disposed on the circumference of the stator.

In the stator are also formed three linear bores serving as cylinders for three pistons 5, 5¹, 5¹¹, including slidable seals 45 which each engage by a tenon into a recess 40 at that end of one of the arcuate vanes which can emerge into channel 3. Each piston is sealed in its cylinder by a suitable packing. The inner ends of the three cylinders open into a common fluid conduit 7. It will be seen that liquid pressure applied in conduit 7 will drive the pistons 5, 5¹, 5¹¹ outwardly and cause a corresponding arcuate movement of the associated vanes, bringing one end of each vane into the channel 3.

On the rotor 2 is mounted a radially inwards projecting member 6 constituted by forward and rear radially-acting cams and between them a portion which forms a sliding seal with the stator and thus serves effectively to close the channel 3. The intermediate portion between the cams is long enough to close both ends of an arcuate passage simultaneously.

During rotation of the rotor as the portion 6 rides past each vane positioned with one end in the channel, the forward cam (considered in the direction of rotation) drives the vane back into its arcuate housing. At the same time the rear cam allows the adjustment vane to emerge by a corresponding amount from its housing. Thus the inward and outward movements of the cams always compensate for each other, and there is no to and fro movement of liquid transmitted back into the braking

2

pressure conduit 7. During this corresponding inward and outward movement of any two of the vanes, the third vane remains out to a predetermined amount to brake the liquid flow in channel 3 to the desired extent.

5 To permit escape of liquid from the arcuate housing of the particular vane being driven back in, there is provided a recess 32 in the sealing portion of projection 6.

Each vane 4, 4¹, 4¹¹ has a number of liquid flow grooves formed in it to ease its movement in its arcuate passage, see FIG. 2. The vane has six grooves in all, 8, 9, 10, 11, 12 and 13. FIG. 5 is a cross-sectional view showing the configuration of representative grooves 10 and 13. Groove 10 on one face is connected to groove 8 on the other face by a passage 29 and to groove 9 on 15 the other face by a passage 29¹. Groove 13 on one face is connected by a passage 30 to groove 11 on the other face, and by a passage 30¹ to groove 12 on the other face.

When the rotor 2 rotates and there is liquid in channel 20 3, this liquid is driven round by projection 6. When any vane 4, 4¹ or 4¹¹ is raised into channel 3, a circumferentially-acting force is exerted on the vane and such force would tend to join the vane in its arcuate passage. However, any liquid pressure exerted on one side of the 25 vane will (according to the direction of rotation) be transferred through the vane so as to act in opposite direction between the vane and its passage walls, i.e. liquid pressure applied in grooves 8 or 9 is transmitted to groove 10, and that applied to grooves 11 or 12 is transmitted to 30 groove 13. This ensures that the vanes do not join, and remain readily movable under the control of their respective pistons.

The thrusts exerted on the ends of the vanes 4, 4¹, 4¹¹ by the liquid under pressure in channel 3 (if such 35 vanes were perfectly symmetrical) would be equal and opposite and the vanes would not tend to shift. However, one end of each vane is provided with a lug 14, making them unsymmetrical. There is thus an excess of force exerted by the liquid in channel 3 on one end of the 40 vane, and this is balanced by the outward thrust of the respective control piston 5, 5¹ or 5¹¹. Accordingly, for a given thrust exerted on the piston, the associated vane moves out into the channel 3 until the forces on it are balanced. So long as such thrust is exerted on the piston, 45 the vanes provide a constant pressure in the channel 3, despite any variations of speed of rotation or viscosity.

The construction need not be limited to a single projection 6 and a single set of three vanes 4, 4¹, 4¹¹. More than one projection 6 could be used, in conjunction with 50 a corresponding number of sets of three vanes.

To permit use of more than one projection 6 it is desirable to be able to reduce the total length of each projection. For this purpose the end of each vane passage remote from the associated piston may be closed, in which 55 case the intermediate sealing portion of the projection 6 may be reduced in length to the width of the end of the vanes. Liquid can still circulate in the vane passages, because of existence of the passages 29, 29¹ and 30, 30¹.

It is desirable to obtain a mechanical locking action 60 of the rotor to the stator when they are relatively stationary. For this purpose, see FIG. 3, there is provided a piston 31 having its smaller end engaged through a packing gland into the brake-pressure liquid conduit 7. A larger head 15 on this piston is engaged in a cylinder 65 bore in the stator 1 opening through a hole 17 into channel 3. A compression spring 16 tends to force the piston downwards in FIG. 3. When braking pressure is exerted on the liquid in conduit 7, although this might tend to lift the piston 31, there is at the same time an 70 increase of pressure in channel 3 which acts on the larger piston 15 so that the pistons 31, 15 do not lift. As there may be a slight delay in build up of increased pressure

in channel 3, when braking pressure is applied in conduit 7, the hole 17 is made relatively small to prevent rapid outflow of liquid so that the pistons 31, 15 cannot rise very far during that delay.

When rotation stops, the pressure in channel 3 falls considerably, so that if braking pressure is maintained in conduit 7, the pistons 31, 15 will eventually be able to rise. On piston 31 is mounted a cross-bar carrying teeth 18, 18¹ which are then moved into mesh with other teeth 19, 19¹ on the rotor, whereby the rotor becomes locked to the stator. When braking pressure is removed from conduit 7, the spring 16 drives pistons 31, 15 downwardly and disengages teeth 18, 18¹ and 19, 19¹.

It is also desirable that the brake shall act automatically in case of rupture of the control ducts. For this purpose there is provided the arrangement of FIG. 4. In a cylinder bore 25 in the rotor 1 is slidably sealed a piston 20 urged downwardly by a compression spring 21. The rod of the piston is slidably sealed in a narrower cylinder bore connected to the braking conduit 7. This downward pressure exerted by the spring is sufficient to cause maximum braking pressure in conduit 7.

For normal control of the brake by an operator, there is provided a cylinder 22 housing a slidable piston 23 urged inwardly by a spring 24 and under the action of a foot pedal 27 having a camming portion 28 acting on the piston rod. The cylinder bores 25 and 22 are in communication and are liquid filled. With no pressure exerted on the pedal, spring 24 pushes piston 23 inwardly and thus lifts piston 20 against its spring 21, so that no braking pressure is exerted in conduit 7. When pressure is applied on the pedal 27, the piston 23 moves correspondingly outward, allowing piston 20 to descend and exert braking pressure in conduit 7.

If there should be either a rupture or a leak in the bores 25, 22, the piston 20 will no longer be held up and automatically sets the brake fully on.

I claim:

1. A liquid brake comprising a central stationary part, a revolving rotor drum surrounding the stationary part and defining therewith a duct filled with fluid, at least one projection dividing said duct into sections, said projection comprising a forward and rear cam on the revolving part, an arcuate recess in said projection between said forward and rear cams, a plurality of arcuate passages symmetrically disposed in said stationary part, each of said passages communicating with said duct, an arcuate vane slidably disposed in each of said passages, each of said vanes having a first and second set of grooves disposed in opposite arcuate faces thereof, each of said sets comprising three separate grooves, a first passage through said vane for connecting the two outer grooves of said first set with the inner groove of said second set, a second passage through said vane for connecting the two outer grooves of said second set with the inner groove of said first set, said vanes being movable partially out of said arcuate passages so as to have one end disposed in said duct, a plurality of cylinder bores equal in number to said vanes located in said stationary part, said cylinder bores communicating with a common liquid conduit, a movable piston within each of said cylinder bores, means for coupling a separate one of said pistons to one end of each of said vanes, and a means for applying pressure to the liquid in said common conduit

for moving said pistons to force said one end of said vanes into said duct, the cams of said projection being disposed so that the forward cam pushes said one end of one of said vanes into its arcuate passage while the rear cam permits the said one end of the following vane to emerge from its arcuate passage to a corresponding extent.

2. The apparatus of claim 1 wherein the central stationary part includes a radial two-part cylinder bore having a part of greater diameter and a part of smaller diameter, the smaller part communicating with said common conduit and the larger part communicating with said duct, a two-part piston of corresponding diameters in said bore, first radially-inwards facing teeth on said rotor drum, second radially-outwards facing teeth on said two-part piston positioned to engage with said first teeth and spring means in the bore serving to urge the piston in the direction to separate said teeth.

3. A liquid brake comprising a cylindrical stator, a rotor drum disposed coaxially with and rotatable about the stator, said rotor defining with the stator an annular channel filled with liquid, a projection on the internal circumference of the rotor, said projection having forward and rear radially-acting cams and a part between said two cams forming a sliding seal with the stator, said stator including three arcuate passages opening into the channel defined between the stator and rotor, three arcuate vanes disposed slidably one in each arcuate passage and being movable partially out of their passages so as to have one end disposed in the channel, each vane having longitudinal grooves in its opposed arcuate faces and internal passages forming a communication between grooves on said opposed faces for balancing of liquid pressure at each arcuate face of the vane, the vanes being symmetrically spaced on the circumference of the stator and the dimensions of the forward and rear cams being such that as one cam pushes a vane back into its passage the other cam permits another vane to emerge from its passage to a corresponding extent, said stator including three cylinder bores communicating with a common conduit, three pistons disposed one in each bore and each coupled to that end of a vane which is movable into the channel, liquid in the cylinder bores and common conduit, means for applying pressure to the liquid in said common conduit for moving the pistons to force an end of each vane into the channel, the stator including a radial two-part cylinder bore having a part of greater diameter and a part of smaller diameter, the smaller part communicating with the common conduit and the larger part communicating with the channel, a two-part piston of corresponding diameters in said bore, first radially-inwards facing teeth on the rotor, second radially-outwards facing teeth on the two-part piston positioned to engage with said first teeth, and spring means in the bore serving to urge the piston in the direction to separate said teeth.
